UNITED STATES PATENT OFFICE.

HARVEY GILES, OF BROOKLYN, NEW YORK, ASSIGNOR TO ARTEMAS WARD, OF NEW YORK, N. Y.

COIN-CONTROLLED VENDING MACHINE.

Application filed November 20, 1919. Serial No. 339,268.

To all whom it may concern:

Be it known that I, HARVEY GILES, a citizen of the United States, and a resident of Brooklyn, in the county of Kings and 5 State of New York, have invented certain new and useful Improvements in Coin-Controlled Vending Machines, of which the following is a specification.

The invention pertains more particularly 10 to coin-controlled vending-machines for the sale of confections, and it resides in the novel features, structure and combinations of parts hereinafter described, and particularly pointed out in the claims.

15 Vending machines of the class to which my invention pertains are provided with vertical trays adapted to receive vertical columns or stacks of the pieces of the confection or the like to be sold, an operating 20 handle or rod exposed at its outer end, ejector mechanism operable from said handle upon the introduction of a proper coin to the machine, means for directing the sold pieces of confection to an exposed position 25 for removal by the purchaser, means for collecting the proper coins introduced to the machine, such as one cent pieces, and means for returning to the purchaser an improper 30 coin, such as a ten cent piece, which might be introduced to the machine by mistake. These machines are also provided with means for closing the coin slots as the trays become emptied.

35 It has been found that machines of the class to which my invention pertains are so complex and delicate in their mechanisms as to entail considerable loss to the owner for repairs and considerable annoyance to purchasers in the loss of coins introduced to the machines which have become out of order. It has also been found that machines 40 of the class referred to are very roughly handled by some persons when said machines are located in public places, as in 45 railway stations, street corners and the like, and that deliberate attempts are frequently made to rob the machines, all this resulting in machines of certain character and construction, at present largely in use, becoming impaired in their operative mechanism.

50 One object of my invention is to provide a vending machine of the class referred to which will be of such particular construction and durable character as to minimize the 55 necessity for repairs and also minimize the

danger of disarrangement of the mechanism by persons unnecessarily and violently operating the exposed operating rod or handle. A further purpose of the invention is to provide novel means for assuredly 60 directing the sold pieces of goods to the customer, and a further purpose of the invention is to provide novel and effective means for closing the coin slots one after another as the trays become emptied of their 65 pieces of confection. A further purpose of the invention is to provide novel goods ejector mechanism for dislodging the goods from the lower ends of the trays, as said goods are sold, so that they may assuredly 70 pass to the customer, the mechanism also being so arranged as to prevent the clogging of the pieces of confection at the lower ends of the trays. A further purpose of the invention is to provide novel, efficient 75 and durable means for properly actuating the goods ejectors, and also means for preventing the clogging of the operative mechanism by paper or the like which may be 80 children or the like be inserted downwardly 85 through the coin-slots.

The coin-controlled mechanism of my invention comprises various features and details of construction, all of which will be better understood from the specific explanation thereof hereinafter presented and which may not be referred to at this place without elaborate introductory description.

The invention will be fully understood 90 from the detailed description hereinafter presented, reference being had to the accompanying drawings, in which:

Fig. 1 is a front elevation, partly broken away, of a coin-controlled vending machine 95 constructed in accordance with and embodying my invention;

Fig. 2 is a vertical section, partly broken away, through the same taken on the dotted line 2—2 of Fig. 1, the operative mechanism and coin box being omitted;

Fig. 3 is a corresponding view, taken on the dotted line 3—3 of Fig. 1, illustrating the coin mechanism in position, the lower front door of the casing in its open position, the coin box in position to be inserted within the casing and the front of the casing in position to be established in position at the front of the goods-holding trays for closing the front of the casing.

Fig. 4 is a top view of the coin-receiving 110

box or receptacle to be interposed below the operative mechanism shown in Fig. 3 and which box is shown in vertical section in Fig. 3;

5 Fig. 5 is a vertical section, partly broken away, and on a larger scale, through the lower portion of the vending machine of my invention, taken on the dotted line 5—5 of Fig. 8 and showing all the parts of the mechanism in their normal inoperated position;

10 Fig. 6 is a corresponding view through a portion of the vending machine taken on the dotted line 6—6 of Fig. 8, and showing an introduced coin in position to permit a sale to be made;

15 Fig. 7 is a like view showing the parts of the mechanism as having been altered in their relation, by the pulling outwardly of the operating rod or handle to effect a sale;

20 Fig. 8 is a horizontal section through the machine taken on the dotted line 8—8 of Fig. 5;

25 Fig. 9 is a corresponding section illustrating the relation of the various parts of the mechanism to one another after the operating rod or handle has been pulled outwardly for the purpose of effecting a sale;

30 Fig. 10 is a vertical section through a part of the front portion of the machine taken on the dotted line 10—10 of Fig. 5;

35 Fig. 11 is a bottom view of the operative mechanism of the machine and detached therefrom with all the parts shown in their normal inoperated position and relation;

40 Fig. 12 is a corresponding view of the same illustrating the relation of the parts after the operating rod or handle has been pulled outwardly to about one-half of its stroke;

45 Fig. 13 is a corresponding view of the same illustrating the relation of the parts of the operative mechanism after the operating rod or handle has been pulled outwardly to the full extent of its stroke;

50 Fig. 14 is a horizontal section through a portion of the mechanism of the machine taken on the dotted line 14—14 of Fig. 5, the operating rod being in its initial position;

55 Fig. 15 is a corresponding section through the same illustrating the same parts of the mechanism in the relation they will take when the operating handle is pulled outwardly without a coin having been introduced into the mechanism;

60 Fig. 16 is a horizontal transverse section through a part of the lower portion of the machine and showing the parts in their normal relation, taken on the dotted line 16—16 of Fig. 10;

65 Fig. 17 is a horizontal view, partly in section, of a portion of the same, illustrating a change in the relation of the parts from that shown in Figs. 14 and 15; Fig.

having been pulled outwardly to its full extent after a coin has been introduced into the mechanism;

70 Fig. 18 is a vertical section through a portion of the operative mechanism of the machine, taken on the dotted line 18—18 of Fig. 8;

75 Fig. 19 is a top view, partly in section, of one of the goods-ejector carrying slides, the figure being a top view with the upwardly projecting ears for the pivoted goods-ejector shown in section, the section being on the dotted line 19—19 of Fig. 20;

80 Fig. 20 is an edge elevation of the same showing the pivoted goods-ejector in its normal position;

85 Fig. 21 is a vertical section, looking rearwardly, through a portion of the front part of the machine taken on the dotted line 21—21 of Fig. 7 and showing the normal initial relation of the parts of the mechanism;

90 Fig. 22 is a vertical section of the same, taken on the dotted line 22—22 of Fig. 6, showing the relation of the parts just prior to the outward pull of the operating rod but with a coin shown as having been introduced through one of the coin slots preparatory to the operation of the machine;

95 Fig. 23 is a rear view of the lower portion of the several trays of the machine and of the means connected therewith for directing the sold pieces of confection downwardly;

100 Fig. 24 is a horizontal section through a portion of the same, taken on the dotted line 24—24 of Fig. 23, and

105 Fig. 25 is a horizontal section through the lower front hinged door of the machine taken on the dotted line 25—25 of Fig. 5; Fig. 25 shows the lower surface of the horizontal top of said door and the shutters mounted thereon for closing the coin slots when the trays are empty.

110 In the drawings, 30 designates the exterior casing of the machine as a whole, said casing comprising a back 31, sides 32, a top 33, a bottom 34, a lower hinged front section 35 and a removable front or door 36. In rear of the door 36 is formed a chamber for the tray, numbered as a whole 37, for holding the stacks or vertical columns of confections, and within the lower portion of the casing is formed a chamber for the operative mechanism of the machine and also for a coin-receptacle 38 which receives the coins

115 after they have left the operative mechanism and from which the coins may be removed, when desired, after the front 36 has been removed to free the lower front section 35 so that it may be turned downwardly and forwardly, or to the position shown in Fig. 3, which also shows the coin-receptacle 38 as

120 having been withdrawn from the casing of the machine. When in the machine the coin receptacle 38 rests upon bars 39 fastened to

125 130

the opposite sides of the machine and its rear side abuts against vertical bars 40, which may be integral with the bars 39. At the rear of the coin box or receptacle 38 is provided a chute 41 down which the pieces dislodged from the tray may slide to an opening 42 below the front section 35 of the casing and from which opening said pieces may be removed by hand.

10 The lower front section 35 is preferably of metal and faced on its exterior by a block of wood, as shown, having a recess 43 there-in for the fingers of the operator and a slot 44 through which the operating rod or handle 45 may be moved forwardly and rearwardly. The metallic portion of the front section 35 is numbered 46 and it has a slot 47 in line with the aforesaid slot 44 through which the operating rod or handle 45 may have its movement. The lower opposite edges of the plate 46 are formed or provided with ears 48 through which a pivot rod 49 passes, said rod 49 serving to hinge the front section 35 between the main sides of the casing 30. The upper end of the plate portion 46 of the front section 35 is bent rearwardly, as shown in Fig. 5, to form a covering plate 50 for the operative mechanism of the machine and to afford a shelf receiving the lower edge of the front 36, as well as to provide other facilities hereinafter mentioned. The lower inner portion of the section 35 has secured upon it horizontal pins 51 which, when the coin receptacle 38 is in position on the supporting bars 39, abut against the vertical front of said receptacle and bind the receptacle in stationary position. At its upper opposite side edges the front section 35 and more particularly the metallic portion 46 thereof, is equipped with slotted ears 52 which, when said section 35 is turned upwardly to closed position, pass upon screws 53 extending inwardly from the opposite sides 32 of the general casing, said screws 53 serving as stops for the front section 35 and also as means for preventing lateral movement of said section 35 as well as upward or downward movement of said section in any attempt to pry the section 35 to open position.

The upper horizontal plate member 50 of the front section 35 has a front vertical bar 54 rigidly secured upon it and extending from one side edge to the other of said plate 50, and the rear edge of said plate member 50 has upwardly extending integral lugs 55, between which and the bar 54 is formed a space which receives the lower end of the front 36 and serves to aid in locking the lower end of said front 36 in position. The sides 32 of the main casing are provided in line with the seat or space formed between the bar 54 and lugs 55 with inwardly projecting pins or studs 56, shown by dotted lines in Fig. 5 and full lines in Fig. 3, adapt-

ed to recesses 57 provided in the lower side edges of the front 36, said recesses being formed in the metal covering strip applied to the sides and lower edge of said front 36, and said pins or studs 56 being formed on metal plates 58 (Fig. 3) secured to the inner facing surfaces of the sides 32. When the lower front section 35 is turned upwardly to position so as to carry its cover plate member 50 above the operative mechanism 75 of the machine, the front door 36 is placed upon said plate 50 between the bar 54 and lugs 55, the recesses 57 in said front or door being lowered upon the studs or pins 56, and thereupon the upper end of the front door 36 80 may be secured to the top 33 of the casing by means of a key-lock 59. When the front door 36 is placed in position its rear vertical side edges abut against vertical shoulders 60 on the facing sides of the main casing and 85 its lower opposite corners enter recesses 61 afforded by said sides of the main casing. When the front door 36 is locked in position it is securely held against being pulled outwardly by the lock 59, front walls of the recesses 61, studs 56 and the front bar 54 of the plate 50. The shoulders 60, rear wall of the recesses 61, pins or studs 56 and rear lugs 55 prevent the front 36 from being pushed inwardly from over the said plate 50. 90

The lower front section 35 is of very durable character and it is held against opening movement by the presence of the front door 36, studs or pins 56 and recesses 57. It is only necessary therefore to provide 100 one key-lock for the entire machine, that being the lock 59.

The cover plate 50 of the lower front section 35 is formed with coin-entrance slots 62, there being one coin-slot 62 for each section of the main tray 37, and these slots being at the front of the bar 54. Upon the lower side of the plate-member 50 of the lower front section 35 I provide a series of shutters 63 for closing the coin-slots 62 as 105 the sections of the tray 37 become emptied of the pieces of confection. The shutters 63 are formed of strips of metal having elongated slots 64 and freely held against the lower surface of the plate member 50 by 110 means of the screws 65 whose heads support the shutters 63 and upon which screws said shutters may have a sliding movement to close or open the coin-slots 62. The inner or rear ends of the shutter plates 63 are 115 bent downwardly, as at 66, and said shutter plates 63 are normally held in a rear position, leaving the coin-slots 62 open, by means of flexed springs 67 secured to the lower side of the plate-member 50 on screws 120 68 and engaging studs 69 on said shutter plates 63, as shown in Fig. 25. The forward ends of the shutter plates 63 are formed with slots 70 which coincide with the coin-slots 62 so that coins introduced to the 125 130

machine must pass downwardly through the slots 62 and also through the slots 70. When the shutter plates 63 are pushed forwardly, by the means hereinafter described, 5 said plates carry their slots 70 from alignment with the coin-slots 62 and present their solid surfaces below the said slots 62 so as to prevent the entrance of coins to the machine, this taking place as the sections of 10 the tray 37 become emptied.

That portion of the machine which may be designated as the operative mechanism and which is located above the coin-receptacle 38 and partly below the cover plate member 15 50 of the front section 35 and partly below the main tray 37, may be handled as a unit, and this mechanism comprises a stationary main supporting plate 71 having downwardly and then inwardly turned side edge 20 portions 72 which are adapted to rest upon side bars 73 fastened to the facing sides 32 of the main casing and which may be integral with the bars 39, 40, being so shown in Fig. 2. The bars 73 have upwardly turned 25 front fingers 74 and at the rear ends of said bars 73 are formed recesses 75 into which the rear ends of the edge members 72 of the plate 71 may pass and be thereby held against upward movement. The front fingers 74 of the bars 73 prevent forward movement 30 of the operative mechanism even when the front section 35 is turned downwardly to its open position. The mechanism carried by the plate 71 is bodily inserted into 35 the chamber of the machine and upon the supporting bars 73, the side edges of the plate 71 being inserted downwardly below the screws 53 and on a tilting action slid along the bars 73 until their rear ends are 40 within the recesses 75.

The plate 71 is shown in top elevation in Fig. 9, and the edge portions 72 of said plate 71, where the same rest upon the supporting bars 73, are turned downwardly 45 and then inwardly, as aforesaid, forming horizontal U-shaped run-ways or guides 76, as shown in Fig. 22, to receive and guide a sliding bar 77, shown in bottom elevation in Fig. 13, and which carries a portion of the 50 operative mechanism, as hereinafter explained.

The plate 71 has at its rear edge, a downwardly extending bar flange 78 and a deflecting downwardly and rearwardly inclined flange 79, the latter aiding in the passage 55 of the discharged confections to the chute 41 (Fig. 5). The plate 71 has adjacent to its rear edge a vertical bar 80, which is recessed, as at 81, (Fig. 9) to permit the passage below it of horizontally 60 slidable plates 82 upon which, between ears 83 thereof, are pivotally mounted the goods-ejectors 84. In Fig. 9 I show three of the plates 82 in their inoperated position and 65 one of said plates, near the middle of said

figure, in its operated position, in moving to which it carried its goods-ejector 84 against the lower piece of confection in the section of the tray 37 above it to discharge said piece, said piece, when discharged, 70 falling upon the rear exposed portion of said plate 82 and resting thereon until said plate 82 has moved forwardly to its initial position, at which time said plate 82 carries the piece of confection against the vertical 75 bar 80 and thereby said piece becomes arrested and finally unsupported and descends down the inclined flange 79 of the plate 71 and falls upon the chute 41. The bar 80 serves to guide the sliding plates 82 80 and also to strip the pieces of confection as sold from said sliding plates after they have been moved rearwardly to receive said pieces and then return forwardly to their initial position. The bar 80 is preferably 85 formed with forwardly projecting fingers or auxiliary plates 85 which aid in retaining the sliding plates 82 firmly upon the bed-plate 71. The plates 82 are formed with slots 86 through which screws 87 pass for 90 aiding in guiding said plates on their rearward and forward movements and also in holding said plates down upon the bed-plate 71. The screws 87 are illustrated in Figs. 6 and 7 and are concealed in Fig. 9 below 95 the goods-ejectors 84. The sliding plates 82 and goods-ejectors 84 are shown in detail in Figs. 19 and 20, and the specific features of the plates 82 and goods-ejectors 84 will be referred to hereinafter, it being 100 intended at present to give some detailed explanation as to the parts supported upon the bed-plate 71. It may be mentioned, however, that the goods-ejectors 84 are metal plates pivotally secured at intermediate portions between the ears 83 and normally stand at an inclination, as shown in Fig. 20, inclining downwardly and forwardly and terminating adjacent to the front ends of the plates 82. The forward 110 portions of the goods-ejectors 84 are weighted to overbalance the rear portions of said goods-ejectors so as to normally keep the rear ends of said ejectors in line with the lower piece of confection in the 115 sections of the tray 37. The forward ends of the goods-ejectors 84 are preferably flanged downwardly, as at 88 (Fig. 20) to rest upon the forward ends of the sliding plates 82. 120

At the front of the bar 80 the bed plate 71 has two vertical standards 89 having reduced upper ends 90 which enter openings in the upper forwardly bent ends of brackets 91 which are secured upon the face of the 125 main tray 37, as shown in Figs. 5, 6, 7 and 8 and serve to aid in supporting the tray 37 in vertical position.

It may be mentioned here that the tray 37 has secured to the lower ends of its opposite 130

sides hook-plates 92 (Fig. 3) which when the tray is in position have their depending fingers 93 engaging the rear edges of the bed plate 71, this engagement of said fingers 5 with said bed plate serving to aid in maintaining the tray 37 in correct position. The novel features of the tray 37 reside, however, in the means provided at the rear side of its lower end for directing the pieces of confection, as sold, to the chute 41 and these features will be explained hereinafter.

At its forward edge the bed plate 71 is flanged upwardly to form a rigid vertical plate 94, between which and a forward substantially corresponding movable plate 95 the coins pass from the coin slots 62. The plate 94 is stationary and is equipped with means for arresting iron or steel pieces or discs and also for catching washers and deflecting improper coins, such as a ten-cent piece which might be introduced to the machine by mistake, so that such pieces will return to the purchaser. In Fig. 21 I illustrate the forward face of the plate 94, 20 and in Fig. 22 I illustrate in elevation the rear face of said plate. The plate 94 is formed with openings 96 near its upper edge and upon the rear face of said plate 94 I secure a bar or strip of metal 97 carrying at its ends magnets 98 which project through the openings 96 and are exposed at the forward face of said plate 94, the purpose of these magnets being to attract iron and steel pieces which might be introduced 30 to the machine. The plates 94 and 95 have a normal separation suitable for the passage of a coin by means of ribs 99 (Fig. 21) provided on the front face of the plate 94 and against which the forward plate 95 abuts 40 when said plate 95 is in its normal inoperated position. The ends of the magnets 98 are adjacent to the path a coin or an iron or a steel disc would have to take after being introduced through the coin slots 62 and 45 hence said magnets would arrest an iron or a steel disc and prevent it from reaching the operative mechanism of the machine. The forward plate 95 carries stripper plates 100 which project horizontally through 50 openings in the plate 94 just below the magnets 98, and should an iron or steel disc become arrested by a magnet 98 and the handle 45 is then drawn forwardly the movement of the handle will be communicated, by 55 the means hereinafter described, to the forward plate 95 with the result that said plate 95 will be moved from the position in which it is shown in Fig. 6 to about the position in which it is shown in Fig. 12, this being 60 a part-way forward position for the plate 95, its complete forward position being illustrated in Fig. 7, and when the plate 95 is thus moved outwardly, with an iron or steel disc held by a magnet 98, the stripper plate 65 100 adjacent to said magnet would follow

forwardly with the plate 95 and knock the disc from the magnet. The disc caught by a magnet will roll around the curved end of the magnet and reach a point where it will be out of the vertical path of the coin-testers, hereinafter described, and move against the narrow neck portion of a stripper 100, and thereafter as the plate 95 is moved forwardly the broader head portion of said stripper will engage the disc and cause the same to descend at one side of the vertical plane of the coin testers and fall between the plates 94, 95 and to the front of the coin box 38, said disc then descending to the lower portion of the chute 41 without having been permitted to effect a sale.

Upon the rear face of the plate 94 are pivotally secured weight testers and washer catchers 101, the outline of which is illustrated in Figs. 6 and 7. The devices 101 are weighted at their lower ends and formed with fingers 102 and 103. The fingers 102 stand in the vertical path of the coins fed to the machine and if an introduced coin is of proper weight it will on striking the finger 102 turn the weight tester 101 so that the finger 102 will move downwardly and permit the passage of the coin to the further coin testing devices to be hereinafter described, a coin numbered 104 being shown 90 in Fig. 6 as having passed downwardly to said coin testing devices. After the tester 101 has been turned by a proper coin moving the finger 102 thereof downwardly said tester will return to its normal position 100 shown in Fig. 6 due to the weighting of the lower end of the same. Should the article introduced to the machine have been a washer or a coin with a hole in it instead of a proper coin and of the proper weight of the coin required, such washer or coin having a hole in it might turn the finger 102 downwardly but in doing so the finger 103 of the combined tester and washer catcher 101 would be turned forwardly and enter 105 the hole in the washer or coin and suspend such washer or coin, thereby preventing it from passing downwardly to the operative mechanism of the machine. Thereafter on the outward movement of the forward plate 95 the washer or the coin with a hole in it would fall from the finger 103 and descend to the chute 41. If a light weight coin should be fed to the machine it will be arrested upon the finger 102 of the tester 101, and then when the plate 95 is moved forwardly such coin would roll from over the lateral edge of the finger 102 and descend on a path at one side of the vertical path for proper coins, and such light weight coin would then fall between the plates 94 and 95 and reach the chute 41.

At each vertical edge of the plate 94 is a rearwardly projecting arm 105 having upper and lower laterally turned flanges 106 130

(Figs. 18, 22) to form a guide-way for arms 107 secured to the end portions of the plate 95 and projecting rearwardly between said flanges 106. Each arm 105 has 5 a downwardly projecting rear member 108 to which is pivotally secured a double-ended lever 109, as shown more fully in Fig. 18. The upper end of the lever 109 is formed with a vertical slot 110 into which passes a 10 pin 111 secured to the rear end of the arm 107. As the lever 109 is turned on its pivot during the outward movement of the operating rod or handle 45 said lever will, acting through the arm 107, push the front plate 15 95 forwardly, so as to cause a separation of the plate 95 from the plate 94. The plate 95 and parts connected therewith are automatically returned to their normal position during the return movement of the operating rod or handle 45 to its initial position by means of a spring 112 whose forward 20 end is secured to said plate 95, and whose rear end is secured to the upper end of a vertical post 113 fastened at its lower end 25 upon the main bed plate 71.

The plate 94 at the forward edge of the bed plate 71 is also equipped with downwardly and rearwardly inclined coin ejector arms 114 whose rear ends are disposed 30 slightly above the sliding plates 82 and serve to force the coins carried against them from the coin-carrying devices, as herein-after explained. The arms 114 are stationary and rigid with the plate 94.

35 Upon the bed plate 71 and disposed between the pairs of sliding plates 82 are pivotally secured locking dogs 115, these dogs being in the shape of arms secured by pivots or screws 116 upon the bed plate 71 and 40 having at their outer edges three teeth 117, 118 and 119, the outer ends of which teeth are in different vertical planes. The pairs of dogs 115 are normally spaced apart to their full extent by means of flexed springs 45 120 engaging the rear ends of the same and acting to turn said dogs in a direction from each other as far as the stops 121 will permit, these stops being pins fixed to the bed plate 71 and adapted to be engaged by 50 shoulders formed on the shank ends of the dogs 115, as clearly shown in Figs. 8 and 9.

The sliding plates 82 adjacent to the sides of the dogs 115 are formed with a tooth 122 and this tooth together with its cooperating dog 115 is to ensure a full rearward stroke of the sliding plates 82 and goods ejectors 84 whenever a proper coin has been introduced to the machine and the operating handle 45 has been started on its forward 60 movement. The rear outer side edges of the dogs 115 are curved, as shown in Fig. 9, and these edges are engaged by the coin when introduced to the position shown in Fig. 6 and the handle 45 is pulled outwardly. When the handle 45 is pulled outward-

ly the coin 104 is carried inwardly and at its edge engages the dog 115 at the point at which it was introduced and in riding against the rounded cam edge of said dog operates to turn said dog in a direction from 70 the slide 82 with which the coin is traveling, the result of this being that the tooth 119 of the dog is carried out of the path of the tooth 122 of the slide and cannot arrest said slide from completing its movement to the 75 position in which the second slide from the bottom is shown in Fig. 9. In the absence of a proper coin being fed to the machine the dogs 115 would not be moved on their pivots and hence would remain in their initial position shown in Fig. 8.

The dogs 115 in every instance co-operate with a proper coin fed to the machine to compel a full movement of the operating rod or handle 45 and the slide 82 85 with which the coin and dog co-operate. When a coin is fed to the machine and becomes arrested between the coin testing devices hereinafter described and the rod or handle 45 is pulled forwardly, the coin is 90 carried against the slide 82 with which it is then in line to move said slide and the goods ejector carried thereby for the purpose of dislodging a piece of goods from the lower end of the tray, and on the 95 movement of the coin rearwardly under the action of the rod or handle 45 the coin not only moves its slide 82 rearwardly but rides against the forward rounded edge of the dog 115 and first turns said dog in 100 a direction from the slide so that the tooth 119 of the dog may be moved laterally to clear the tooth 122 on the slide 82, and then as the coin travels rearwardly and gets just beyond the forward tooth 117 of the dog, 105 the spring 120 engaging the dog will turn the dog laterally toward the coin so that the coin will be at the rear edge of said tooth 117 and in such position prevent the operating rod or handle from being moved to any 110 position which would result in the slide 82 being moved or returned forwardly. If we then pull the operating rod or handle 45 further forwardly the tooth 118 of the dog 115 will be engaged by the edge of the coin and the coin will press the dog laterally in 115 opposition to its spring 120 until the coin has passed by the said tooth 118, when the spring 120 will turn the dog to carry its tooth 118 to the forward face of the coin. 120 The tooth 118 will then by its cooperation with the coin prevent the slide 82 from being moved forwardly. If we then pull the operating rod or handle 45 further outwardly, the coin will leave the tooth 118 of the dog and complete its rearward movement, the coin pushing the slide 82 rearwardly to its full extent and causing the goods ejector 84 to engage the lower piece of confection, forcing the same rearwardly until said piece 125 130

leaves the tray 37 and falls upon the rearwardly projecting end of the sliding plate 82, in which position a piece of the confection is shown in Fig. 7. Then upon the completion of the rearward movement of the slide 82 and goods ejector 84 the coin carrying devices release the coin to fall into the coin box 38, and in order to assure the ejection of the coin, the coin during its rearward movement has its upper edge carried against the lower edge of one of the arms 114 which as shown in Fig. 7 incline downwardly and rearwardly, and at the proper time said arm 114 will force the coin downwardly from the coin-holding devices and thereby compel the release of the coin from the operative mechanism of the machine, the coin having then completed its work. The introduced coin, therefore, is carried against the forward end of a slide 82 carrying a goods ejector 84, and said coin also by co-acting with one of the dogs 115 serves to compel a full rearward stroke of the slide 82 and goods ejector 84. After the coin has been released from the operative mechanism by the full forward movement of the operating rod or handle 45, and the complete rearward movement of the slide 82 and goods ejector 84, the operating rod or handle may be released and it will be automatically returned to its initial position, due to the action of the coiled springs 123 and pivoted levers 124 located below the bed plate 71 and clearly illustrated in Fig. 13.

As many of the sliding plates 82 and goods ejectors 84 as may be desired may be made use of. In the present instance the tray 37 has four sections for the columns or stacks of confection and hence the machine illustrated embraces four of the slides 82 and four goods ejectors 84, one slide and one ejector being intended for each compartment of the tray 37. Each slide 82 will co-operate with the coin and one of the dogs 115, and over each slide and in a position for the coin to ride against its lower edge, is provided one of the coin ejector arms 114.

Having somewhat particularly referred to those parts of the mechanism located above the bed plate 71, I will describe the features of construction located below said bed plate. I have heretofore referred to the fact that the side edge portions 72 of the bed plate 71 are bent downwardly and then inwardly to form guides 76 for a slide 77. The slide 77 is a reasonably narrow bar extending from one guide 76 to the other guide 76, and in Fig. 16 I illustrate the sliding plate or bar 77 with some of its suspended features indicated by dotted lines, and in Figs. 11 and 12 I illustrate said sliding plate or bar 77 with the features suspended therefrom, shown by solid lines. The bar 77 is slotted at its forward edge, as at 125, there being four of these slots 125 and being provided to receive the pins 126 which project downwardly from the forward ends of the slides 82, as shown in Figs. 11 and 20. The sliding bar 77 is, at the entrance of the slots 125, recessed laterally, as at 127 to afford a space within which a coin may be fed, said coin then extending across the slot 125 and being in line with a pin 126 of one of slides 82. The sliding bar 77 is provided at opposite sides of the entrance to the slots 125 with pins 128 which project downwardly and serve as a backing for the coin held in the recesses 127. At its inner rear corners the slide 77 has fingers 129 and these fingers receive the rear ends of the springs 123, the forward ends of said springs being connected with posts 130 projecting downwardly from the forward edge portions 72 of the bed plate 71. When the slide 77 and its parts are moved rearwardly by the forward pull of the operating rod or handle 45, the springs 123 operate to return said slide and its parts to their initial forward position. The sliding bar 77 is given its rearward movement from the operating rod or handle 45 through the medium of the pivoted double-ended levers 124, which are pivotally mounted on brackets 131 fixed to the rear member 78 of the bed plate 71. The outer ends of the levers 124 are slotted, as at 132, and within these slots are screws 133 which are connected with the rear corner portions of the sliding bar 77. The slots 132 prevent any binding action of the levers 124 on the screws 133 during the movement of said levers when actuated by the operating rod or handle 45. The adjacent ends of the levers 124 are recessed out to form cam pockets 134, clearly illustrated in Fig. 11, which engage pins 135 which project upwardly from a cross-bar 136 secured to the upper surface of the rear end of the operating rod or handle 45. The springs 123 preserve the engagement of the cam pockets 134 with the pins 135, said springs always acting to throw the inner ends of the levers 124 against said pins 135. The actuating rod or handle 45 is mounted in a bar frame 137, and is shown in bottom view in Figs. 11, 12 and 13 and in side elevation in Fig. 7. The rear end of said frame 137 is secured to the depending bar 78 of the bed plate 71 and the forward end of said frame 137 is secured to the forward side of the bar member 94 of said bed plate 71, as shown more particularly in Fig. 7, the forward plate 95 being cut away in line with the said frame 137 so that said plate 95 may move forwardly or to the position shown in Fig. 7 without interference from said frame 137. The bottom portion of the frame 137 is slotted as at 138 to receive a bolt 139 which enters the lower rear portion of the rod or handle 45 and aids in guiding said rod or handle and in properly retaining the same within the frame 137, whose front end is slotted, as at 140 (Figs. 14 and 130

15) to aid in positioning and guiding said rod or handle 45.

Directly against the lower surface of the sliding bar 77 I provide coin-tester plates 141 and 142 arranged in pairs, as clearly shown in Fig. 16. The plates 141—142 are adapted to have rearward and forward sliding movements and guide against each other in pairs and are also guided by pins 143 which project from the plate or bar 77, and are clearly shown in Fig. 16. The coin-tester plates 141, 142 have at their forward portions inclined surfaces 144 which cross one end of the recesses 127 for the coins fed to the machine, as shown in Fig. 16. A coin fed to the machine passes downward from the coin slot and between the plates 94 and 95 hereinbefore described and enters the recesses 127 of the plate or bar 77, the coin being arrested at one edge in one of said recesses 127 and at its other edge in the other recess 127 but on the inclined edge 144 of the adjacent coin tester. If the coin should be of proper size or diameter it will become arrested in the manner just specified, but if the coin should be of less than the proper size it will pass entirely through the recesses 127 and by the coin tester and descend to the chute 41, which will return it to the pur-chaser. The plates 141, 142 are therefore coin testers intended to test the size and also the thickness of the coins fed to the machine, the inclined edges 144 of said plates permitting a thin coin of nearly the proper diameter to pass downwardly to the chute 41. The plates or coin testers 141, 142 are equipped with screws 145 and nuts 146 by which in connection with the downwardly projecting lugs 147 on said plates or coin testers and a front downwardly turned edge portion 148 on the bar or plate 77 (Fig. 6), said plates 141, 142 may be adjusted forwardly or rearwardly so as to adapt their inclined edges 144 to the coin recesses 127 and to the character of coin which it may be intended to arrest within said recesses. The nuts 146 are jam nuts and when loosened, the turning of the screws 145 in one direction or the other will serve to move the coin tester plates 141, 142 forwardly or rearwardly. The coin tester plates 141, 142 have a spring tension tending to hold them in their initial normal position, shown in Fig. 16, and this is due to the springs 149 connected with the downwardly bent ends or lugs 147 and to pins 150 which extend downwardly from the plate or bar 77, as shown more clearly in Fig. 13. When a coin is in position in the coin recesses 127 of the bar or plate 77 and against one of the coin tester plates 141 or 142 and the bar 77 is moved rearwardly from the operating rod or handle 45, the coin tester plates move with the said bar or plate 77 except at the latter part of the movement of said plate or bar 77 when said plate or bar

77 advances rearwardly while the coin tester plates 141, 142 are kept from further rearward movement, and during the slight rearward movement of the bar or plate 77 in advance of the coin tester plates 141, 142 the springs 149 of said plates 141, 142 become stretched and then on the first part of the return movement of the bar or plate 77 said springs 149 retract and re-establish the relation of the bar or plate 77 with said coin tester plates. When the bar or plate 77 and coin tester plates carried by it are moved rearwardly the rear ends of said coin tester plates engage stops 151, as shown by dotted lines in Fig. 13 which project downwardly from the main body plate 71 and thereby said coin tester plates become arrested for the proper ejection of the coin, while the bar or plate 77 may continue to move a slight distance rearwardly in advance of said coin tester plates, thereby carrying its coin-recesses 127 rearwardly from the inclined edges 144 of said testers to free the coin and permit the same to be forced downwardly by the coin-ejectors 114.

The levers 124 which actuate the bar or plate 77 become arrested at the full inward movement of said bar or plate 77 by their engagement with rubber buffers 152 secured to the lower rear corner portions of the bed plate 71, as shown in Fig. 13. I also provide the rear end of the operating rod or handle 45 with a buffer 153 to cushion it when it arrives at its inner position with its rear end against the front plate 78 of the bed plate 71.

I will now describe the means provided in my machine for preventing any movement of the goods ejectors 84 and goods ejector slides 82 when the operating rod or handle is pulled outwardly in the absence of the proper coin having been introduced to the machine, and these means comprise a trans-verse-bar 154, shown in bottom elevation in Figs. 11 and 12, slidably mounted against the lower surface of the plate or bar 77 by means of screws 155 and slots 156. The bar 154 is above the operating rod or handle 45 and carries at its front edge a downwardly projecting stud 157 for co-operation with a run-way or groove 158 formed in one side of the upper surface of the operating rod or handle 45. The forward edge of the transversely slid able bar 154 is engaged by the pins 126 which project downwardly from the front ends of the slides 82 for the goods ejectors 84, as illustrated in Fig. 16, and said bar 154 is provided adjacent to the slots 125 in the bar or plate 77 containing the said pins 126, with shoulders 159 (Fig. 11) which are normally adjacent to the said edges of the slots 125, as shown, but do not engage the pins 126, in Fig. 11, being normally held in that position by the engagement of the lug 157 carried by said bar 154 with the

side of the rod 45 and by means of the spring 160 which acts to bind said lug 157 against the side of said rod 45. The spring 160 is normally under tension and serves to normally maintain the bar 154 in the position in which it is shown in Fig. 11, with the lug 157 thereof, yieldingly held against the side of the operating rod 45.

When the operating rod 45 is pulled outwardly in the absence of a coin having been introduced to the machine, said rod will pull the adjacent ends of the levers 124 forwardly to a limited extent, and these levers will move the sliding bar 77 and with it the transversely slidable bar 154 rearwardly, while at the same time the stud 157 will ride against one edge of the said operating rod 45, said edge being the right hand edge of said rod looking at Figs. 14, 15, 16 and 17. During the outward movement of the rod 45, in the absence of the coin, the lug 157 will ride along the edge of the said rod 45 until the inclined surface 161 thereon and located at the entrance to the run-way 158 reaches said lug 157, and at that time the spring 160 connected with the transverse bar 154 will cause said bar to slide transversely and carry the lug 157 along said inclined surface 161 and against the shoulder 162 provided on the rod 45 just in rear of said inclined surface 161, as shown in Figs. 14, 15, 17, for illustration, and upon the arrival of said lug 157 against said shoulder 162 or to the position shown in Fig. 15, said lug in cooperation with said shoulder will arrest the operating rod 45, so that said rod will not be able to perform its regular movement, but can only be moved outwardly in a forward direction toward the operator for the limited distance of the travel of the lug 157 to said shoulder 162. Under these circumstances the levers 124 may only perform a limited movement and the slidable plate or bar 77 and bar 154 can only move rearwardly to a limited extent, that being the extent represented in Fig. 12. During this limited movement of the rod 45, bar or plate 77 and bar 154 the ejector slides 82 and ejectors 84 do not have any movement, it being necessary that a coin shall be introduced to the machine if said slides and ejectors are to be moved. By arresting the operating rod 45 at the end of a very limited outward movement thereof by the stud 157 and shoulder 162, the mechanism of the machine is saved against disarrangement and impairment by any foolish attempted operation of the rod or handle 45.

During the limited forward movement of the rod or handle 45, as just hereinbefore described, the front plate 95 is given a limited forward movement due to the fact that the lower ends of the pivoted levers 109 extend through slots 163 in the bed-plate 71 and enter slots 164 at the ends of the sliding bar

or plate 77, and this forward movement of the plate 95 is of benefit in the event that anyone should have inserted a button or other disk through a coin-slot before pulling on the operating rod or handle 45, the separation of the plate 95 from the plate 94 permitting such button or other substance to fall downwardly to the chute 41. After the rod or handle 45 has been pulled forwardly to the limited extent hereinbefore described or until the lug 157 strikes the shoulder 162 and arrests said rod or handle, the parts moved by the rod or handle automatically return to their initial position, the spring 112 drawing the plate 95 to its normal position, the springs 123 restoring the levers 124 and through said levers the rod 45 and sliding bar 77 to their normal position, and the spring 160 serving to keep the lug 157 against the rod 45 so that said lug will slide forwardly along the inclined surface 161 of said rod and finally move along the flat edge of said rod from the position in which the lug is shown in Fig. 15 to that in which said lug 157 is illustrated in Fig. 14, the various parts of the machine being then returned to the normal initial condition.

With reference to the mechanism just hereinbefore described, including the lug 157 on the bar 154 and the run-way or groove 158 in the operating rod 45, it may be proper at this place to explain the action which takes place when a proper coin has been introduced to the machine and is held by a coin-tester 141 or 142 in a recess 127 of the sliding plate or bar 77 or in the position in which I illustrate a coin 104 in Figs. 6 and 22. When a coin has thus been introduced to the machine and the operating rod or handle 45 is pulled forwardly, the levers 124 will move the sliding plate or bar 77 rearwardly and the coin will be carried against the goods-ejector slide 82, as hereinbefore explained, to effect the ejection of the lower piece of confection in one of the columns of the tray, and the sliding bar 154 will, at its shoulders 159, be caused to engage the downwardly projecting pins 126 carried by the goods-ejector slides 82, the spring 160 shifting the bar 154 sufficiently to carry said shoulders 159 against said pins 126, the result of this being that during the rearward movement of the plate or bar 77 and sliding bar 154, the lug 157 carried by said bar 154 instead of being permitted to ride along the inclined surface 161 of the rod 45 to an extent enabling it to reach the shoulder 162, will be held outwardly in a direction from said shoulder 162 and be permitted finally to engage and ride along the straight edge 165 of the operating rod 45 and thereby travel to the position in which said lug 157 is shown in Fig. 17, the lug 157 then being against the cross-bar 136 and the operating rod or handle 45 having completed its for-

ward stroke. When therefore a coin has been introduced to the machine prior to the pulling forwardly of the operating rod or handle 45, the transversely slideable bar 154 will, by the presence of the coin and the engagement of the shoulders 159 on said bar 154 with the pins 126 carried by the goods-ejector slides 82 prevent such movement of the bar 154 as would cause the lug 157 to reach the shoulder 162 of said rod 45, thereby permitting a full outward or forward movement of the rod or handle 45. In the absence of the coin, the sliding plate or bar 77 and bar 154 travel independently of the goods-ejector slides 82, and hence, after said plate or bar 77 and bar 154 have traveled rearwardly to a limited extent, the shoulders 159 on the bar 154 are carried rearwardly of the pins 126 and therefore said shoulders and pins cannot co-act to prevent such movement of the bar 154 as will permit its lug 157 to ride against the inclined surface 131 of the rod 45 and reach the shoulder 162.

During the rearward movement of the plate or bar 77, bar 154, goods-ejector slides 82 and goods-ejectors 84, with a coin in position, the levers 109 acted on by the plate or bar 77 move the front plate 95 forwardly or to the position shown in Fig. 13 so that anything lodged between the plates 94, 95 may descend to the chute 41.

I have hereinbefore described the action of the dogs 115 in compelling a full rearward movement of the goods-ejector slides 82 when said slides have been started rearwardly, with the plate or bar 77 and bar 154 on a forward pull of the operating rod or handle 45, and hence it may not be necessary to here repeat the operation of said dogs 115 and parts cooperating therewith. The special arrangement and construction of the dogs 115 is important and I believe novel.

The only parts of the mechanism with which the operating rod or handle 45 is connected, aside from being guided in the housing 137, are the levers 124 and, through said levers, the sliding bar or plate 77 carrying the bar 154.

The tray 37 has in each of its four compartments a weight 166 resting upon the pieces of confection, and this weight is concaved at its lower surface, as at 167, as usual, to permit the passage of a goods-ejector 84. The weight 166 performs the usual function of effecting the downward movement of the stack of confections, and in the present instance the weight 166 carries a forwardly projecting plate or blade 168 having a forwardly projecting inclined or cam edge 169. When a column of confections becomes exhausted and the weight descends in consequence thereof, the cam edge 169 of the plate 168 carried by the weight, will ride downwardly against the rear edge of a shutter-plate 63 and move said shutter plate for-

wardly in opposition to the stress of the spring 67 and effect the closing of the coin-slot, so that no further coins may be introduced to the machine with respect to the section of the tray 37 whose goods have become exhausted. The rear edge of the shutter plates 63 have the downwardly turned edges 66, as shown in Figs. 5 and 24, and the plate 168 of the weights 166 engage, at the proper time, said edges 66 of the shutter plates and move said shutter plates forwardly, the shutter-plates being held in their forward closing position by a straight edge 170 on the plates or blades 168, which edge will pass into engagement with the downwardly turned edges or flanges 66 of the shutter plates, as will be understood on reference to Fig. 5.

The tray 37 presents certain novel features which have to do with the proper holding of the pieces of confection, numbered 171, in the sections of the tray and in the proper discharge of said pieces as sold, so that they may fall upon the chute 41. The tray 37 in its several sections is provided with the separated supports 172 for the columns of confections, and at the back of the tray 37 I provide a transverse plate 173 which is hinged at 174 and engaged by a spring 175 which acts to close the plate 173 against the lower back portion of the tray 37, said plate 173 at its lower edge being about on the same horizontal plane with the supports 172 for the columns of confections.

Upon the lower edge of the plate 173 I secure a series of curved plates 177, there being one plate 177 at the back of each section of the tray 37, as shown in Fig. 23. When a piece of confection is pushed rearwardly by a goods-ejector 84, said piece is pressed against the plate 173 and forces said plate to turn toward the back of the machine, and as said plate 173 turns backwardly, the plates 177 hang downwardly, and the discharged pieces of confection are by them in connection with the plate 173 deflected downwardly so that said pieces may assuredly descend upon the then rearwardly projecting ends of the goods-ejector slides 82, said pieces thus attaining the position in which one of said pieces is shown in Fig. 7. Upon the return movement of the operating rod or handle 45, plate or bar 77, goods-ejector slides 82 and goods-ejectors 84, to their initial position or from the position in which said parts are shown in Fig. 7 to that in which they are shown in Fig. 6, the piece of confection resting on the end of the goods-ejector slide 82 will be carried against the stripper-plate 80 and become unsupported, and the hinge plate 177 adjacent to said piece will serve to direct said piece downwardly against the rear flange 79 of the bed-plate 71 and assure the descent of said piece of confection to the chute 41.

82

The coin-box 38 is of the outline clearly shown in Figs. 3 and 4, and said box is cut away at 180 so that it may be inserted in the main casing after the mechanism has been introduced thereinto and without interfering with the frame 137 supporting the operating rod or handle 45. The box 38 is provided with rearwardly projecting flanges 181 which are serrated, as at 182, at their rear edges, the serrations 182 being intended to catch a disk or the like which might be introduced into the machine on the end of a string, the disk falling into the coin-box and the string being caught in one of the serrations 182, the purpose being to prevent the withdrawal of the disk by means of the string. This feature of the construction being a fraud preventative device, is not specifically claimed herein.

20 It may be mentioned that the front plate 95 is formed with vertical openings 183 (Fig. 10) below the strippers 100, these openings being to facilitate the discharge of anything caught between the plates 94, 95 so that the same may fall to the front of the coin-box 38 and upon the lower portion of the chute 41.

In the employment of the machine hereinbefore described, one coin may be introduced for the sale and delivery of one piece of confection on the outward movement of the operating rod or handle 45, or four coins may be introduced to the machine, one at each coin-slot, and under this condition all of the ejector slides 82 and goods-ejectors 84 will be moved rearwardly and each ejector will dislodge a piece of confection from one of the columns of the tray, four pieces of confection being thus sold and delivered on one outward movement of the operating rod or handle 45. In Fig. 9 I illustrate the relation of the parts of the mechanism when only one coin has been introduced and one ejector slide 82 and one ejector 84 forced rearwardly on the forward pull of the rod 45, and should four coins be introduced to the machine, one at each coin slot, and the rod 45 pulled forwardly, all of the slides 82 and goods-ejectors 84 would take the position indicated by the one rearwardly moved slide 82, shown in Fig. 9.

What I claim as my invention and desire to secure by Letters-Patent, is:

1. In a coin-controlled vending machine having a tray for holding a stack of the articles of merchandise to be sold and a manually operative handle, enclosed mechanism comprising a slide operable in a direction toward said tray by means of said handle and having a coin-receiving recess within which the coin is held on edge facing rearwardly in a direction toward said tray, the rear face of said coin being positioned to serve as an abutment to effect the positive dislodgement of merchandise from said tray

when said handle is operated on its goods discharging stroke, a member slidably carried by said slide and affording a lower support for the coin in said recess, a stop in the path of said supporting member for arresting the same against movement during the rearward movement of said slide to effect the dislodgement of the merchandise and before said slide ceases its movement, whereby said slide is caused to carry the coin beyond said arrested supporting member to permit the release of the coin, and means for restoring said supporting member in its relation to said recess after the discharge of the merchandise and during the forward movement of said slide to its normal position.

2. In a coin controlled vending machine having a tray for holding a stack of the articles of merchandise to be sold and a manually operative handle, enclosed mechanism comprising a slide operable in a direction toward said tray by means of said handle and having a coin-receiving recess within which the coin is held on edge facing rearwardly, said coin being utilized as an abutment to effect the dislodgement of merchandise from said tray, a coin-tester and coin supporting member slidably carried by said slide and having an inclined edge crossing an end of said recess and adapted as a support for the coin, a stop in the path of said supporting member for arresting the same during the rearward movement of said slide and before said slide ceases its movement whereby said slide is caused to carry the coin beyond said supporting member to permit the release of the coin, and means for restoring said supporting member in its relation to said recess during the forward movement of said slide to normal position.

3. In a coin-controlled vending machine having an enclosing casing provided with a coin-slot, a tray for holding a stack of the articles to be sold and a manually operative handle, enclosed mechanism comprising a bed-plate, a goods-ejector slide thereon adapted on its operation to effect the dislodgement of an article from said stack, a coin-carrying sliding-plate connected with said handle for rearward and forward movement and having a coin-receiving recess adapted to hold the coin in the plane of a part of said goods-ejector slide, a coin-tester plate slidably mounted on said sliding plate and having an inclined edge crossing one end of said recess and adapted as a coin-support and a stop against which said coin-tester plate is carried on the inward movement of said sliding-plate for moving said coin-tester plate from said recess to thereby release the coin to descend.

4. In a coin-controlled vending machine having an enclosing casing provided with a coin-slot, a tray for holding a stack of

the articles to be sold and a manually operative handle, enclosed mechanism comprising a bed-plate, a goods-ejector slide thereon having at one edge a tooth (122) and adapted on its operation to effect the dislodgement of an article from said stack, a coin-carrying sliding plate connected with said handle for rearward and forward movement and having a coin-receiving recess adapted to hold the coin in the plane of a part of said goods-ejector slide, and means for compelling a full movement of said goods-ejector slide on the operation of said handle, comprising a locking dog pivotally mounted on said bed-plate adjacent to the goods-ejector slide and having at its inner end a tooth in the path of the tooth on said slide and also having side teeth and a rounded end normally in the path of the edge of the coin, and a spring normally holding said dog in operative position, said sliding plate being adapted to carry the coin against the rounded end of said dog for compelling said dog to turn from the path of the coin and said goods-ejector slide, and said dog being adapted after the coin has passed said rounded end to have its teeth projected back of the coin so as to engage the same on any movement of said sliding plate toward its normal position before the goods-ejector has been given its proper inward movement.

5. In a coin-controlled vending machine having an enclosing casing provided with a coin-slot, a tray for holding a stack of the articles to be sold and a manually operative handle, enclosed mechanism comprising a bed-plate, a goods-ejector slide thereon adapted on its operation to effect the dislodgement of an article from said stack, a coin-carrying sliding-plate connected with said handle for rearward and forward movement and having a coin-receiving recess adapted to hold the coin in the plane of a part of said goods-ejector slide, and means for arresting said sliding plate on the movement of said handle in the absence of a coin introduced to the machine, comprising a transverse slide carried by said sliding plate

10 carrying a lug spring pressed against the edge of said handle, a recess in said handle for the passage of said lug when a coin is in the machine, a shoulder on said handle to be engaged by said lug in the absence of the coin for arresting said handle, a pin on said goods-ejector slide projecting downwardly adjacent to said transverse slide, and a shoulder on said transverse slide to engage said pin when said sliding plate, goods-ejector slide and transverse slide are all moved together from said handle, the engagement of said shoulder on said transverse slide with the pin on said goods-ejector slide serving to prevent the lug on said transverse

15 slide from engaging said shoulder on said

handle when the coin is being carried inwardly by said coin-carrying sliding plate.

6. In a coin-controlled vending machine having an enclosing casing provided with a coin-slot, a tray for holding a stack of the articles to be sold and a manually operative handle, enclosed mechanism comprising a bed-plate, a goods-ejector slide thereon adapted on its operation to effect the dislodgement of an article from said stack, a coin-carrying sliding plate connected with said handle for rearward and forward movement and having a coin-receiving recess adapted to hold the coin in the plane of a part of said goods-ejector slide, and means for arresting said sliding plate on the movement of said handle in the absence of a coin introduced to the machine, comprising a transverse slide carried by said sliding plate carrying a lug, a spring-acting against said transverse slide yieldingly pressing the same toward said handle, a shoulder on said handle to be engaged by said lug in the absence of the coin, for arresting said handle, a part on said goods-ejector slide disposed adjacent to said transverse slide, and a shoulder on said transverse slide to engage said part on the goods-ejector slide when said sliding plate, goods-ejector slide and transverse slide are all moved together from said handle, the engagement of said shoulder with said part on said goods-ejector slide serving to prevent the lug on said transverse slide from engaging said shoulder on said handle when the coin is being carried inwardly by said coin-carrying sliding-plate.

7. In a coin-controlled vending machine having an enclosing casing provided with a coin-slot, a tray for holding a stack of the articles to be sold and a manually operative handle, enclosed mechanism comprising a bed-plate, a goods-ejector slide thereon adapted on its operation to effect the dislodgement of an article from said stack, a coin-carrying sliding plate mounted below said bed-plate and having a coin-receiving recess adapted to hold the coin in the plane of a part of said goods-ejector slide, springs normally holding said coin carrying sliding plate in initial position and for returning said plate to such position after the same has been operated, means connecting said sliding plate with the inner end of said handle comprising diverging pivoted levers having a loose connection with the ends of said plate and at their adjoining ends engaging studs connected with said handle, and means for arresting said handle and sliding plate at a predetermined point when said handle is operated in the absence of a coin carried by said sliding plate.

8. In a coin-controlled vending machine having an enclosing casing provided with a plurality of parallel coin-slots, a tray for

holding the articles to be sold and a manually operative handle, enclosed mechanism comprising a bed-plate having at its forward end an upwardly extending vertical plate, a plurality of goods-ejector slides on said bed-plate adapted on their operation to effect the dislodgement of articles from said tray, a coin-carrying sliding plate having coin-receiving recesses to receive the coins from 10 said coin-slots and hold the same on edge and in the plane of portions of said goods-ejector slides, means connecting said sliding plate with said handle for moving said

plate, with said goods-ejector slides, a vertical movable plate at the front of the aforesaid vertical plate and between which plates the coins pass to the recesses of said sliding plate, and means for moving said vertical movable plate forwardly from the other vertical plate on the movement of said sliding 15 20 plate to carry the coins inwardly.

Signed at New York city, in the county of New York, and State of New York, this 3rd day of November, A. D. 1919.

HARVEY GILES.
